UNITED STATES PATENT OFFICE.

FRIEDERICH W. SCHMIDT, OF LOS ANGELES, CALIFORNIA.

SPARK PLUG.

Application filed November 30, 1923. Serial No. 677,789.

To all whom it may concern:

Be it known that I, FRIEDERICH W. SCHMIDT, a citizen of Germany, residing at Los Angeles, in the county of Los Angeles 5 and State of California, have invented new and useful Improvements in Spark Plugs, of which the following is a specification.

My present invention is a spark plug; and it is an especial object of this invention to 10 provide a spark plug which shall be thoroughly reliable in action, being substantially self-cleaning, and capable of uniform and satisfactory operation even under unfavorable conditions of temperature or 15 pressure.

It is an object of this invention to provide a spark plug which can be readily substituted for such spark plugs as are in current use and which shall be substantially 20 self-cleaning even when used in an interior engine or in connection with comparatively heavy oils or under other conditions such as commonly lead to a fouling or unreliable action of a spark plug.

25 Other objects of my invention will appear from the following description of a specific embodiment thereof, and from the appended claims, taken in connection with the accompanying drawings, in which:

30 Figure 1 is an elevational view of a spark plug embodying my invention.

Figure 2 is a bottom plan view of the same.

Referring to the details of that specific 35 embodiment of my invention which I have chosen for purposes of illustration, 1 may be the body of a spark plug, which may be grounded by contact with metallic parts of an engine, into the explosion chamber of 40 which the threaded end 2 may extend, the porcelain insulation 3, or the like, being provided to prevent contact of the inner electrode 4, connected with a suitable source of current, therewith.

45 In order to provide a suitable spark gap between the central terminal 5 of the inner electrode 4 and a supplemental terminal, it being usual to employ either a single supplemental terminal or a plurality of supplemental terminals arranged in the same 50 plane, my novel electrode construction comprises the employment of an outer electrode comprising two pairs of terminals, the inner or nearer pair 6, 6', being shown 55 as in a common plane and spaced more

widely apart than the second or outer pair of terminals 7, 7', the terminals of both pairs being shown as threaded into or otherwise rigidly supported from and in conductive contact with the threaded portion of the body of my spark plug. 60

Although I have not been able to satisfy myself as to the theoretical explanation of the advantages of a spark plug of the character herein shown and described, I find 65 that it is not necessary to form the lower or outer pair of terminals of highly conductive material, although the inner or upper pair of terminals, from either of which a spark may pass to the central electrode 70 even when my spark plug is tested in ordinary air, are preferably formed of the usual conductive material. Even when I have experimentally formed the lower or outer pair of terminals 7, 7' from iron wire, 75 I have obtained highly advantageous results, and I have not found the exact spacing of the outer terminals relatively to one another or relatively to the inner and highly conductive terminals to be a matter 80 of importance, provided only that the said lower or outer terminals be spaced apart, suitable relative intervals between all of the terminals comprising my spark plug being indicated in the drawing, which is 85 drawn to a substantially uniform scale.

Without attempting to indicate whether the utility of the lower or outer pair of terminals lies primarily in a thermal or in an electrical effect, such as an influence 90 upon the distribution of an electric charge or the character or path of a spark passing between one of the mentioned terminals and the central terminal 5, I may add that highly advantageous results herein referred to cannot be obtained by the use of a single over-arching wire in place of the two terminals 7, 7', and also with the placing of the lower or outer terminals substantially at right angles to the inner or 95 upper pair of terminals is both advantageous and convenient, although a slight variation in the angular relationships of the respective pairs of terminals may be regarded as immaterial. 100

105 Although it has heretofore been recognized that there are advantages in the employment of two or more terminals arranged in a common plane and at substantially uniform distances from a central electrode, one 110

known type of spark plug being provided with a central electrode and three cooperating terminals arranged radially thereabout, I regard my described arrangement of two pairs of electrodes arranged at different levels as superior to known electrodes not only in permitting a spark to pass alternatively between a central electrode and any one of a plurality of cooperating terminals 5 symmetrically arranged, but also in producing a substantially new self-cleaning effect which is of the highest importance in the burning of low-grade oils or during operation in cold weather or under high compression, both the reliability of operation and the comparative avoidance of vibration being very marked in the use of my novel spark plug, in any of the usual types of automobile or other explosion engines. 10

Although I have herein described but one complete embodiment of my invention, it will be understood that various features thereof might be independently employed, and also that various modifications might be 15 made therein without departure from the spirit and scope of my invention, as the same is indicated above and in the following claims.

What I claim is:

- 30 1. In a spark plug having a threaded end within which is disposed a central electrode, complementary electrodes projecting from the face of said threaded end, said electrodes having their ends turned inwardly beneath the bottom of said central electrode upon parallel but different planes.
- 35 2. In a spark plug having a threaded end within which is disposed a central electrode, complementary electrodes secured to said threaded end, said electrodes having their ends turned inwardly beneath the bottom 40

of said central electrode upon parallel but different planes.

3. In a spark plug having a threaded end within which is disposed a central electrode, 45 a pair of complementary electrodes projecting from the face of said threaded end upon opposite sides thereof, said electrodes having their ends turned inwardly beneath the bottom of said central electrode, and a second 50 pair of electrodes projecting from said face and having their ends turned inwardly beneath the ends of the first mentioned pair.

4. In a spark plug having a threaded end within which is disposed a central electrode, 55 a pair of complementary electrodes projecting from the face of said threaded end upon opposite sides thereof, said electrodes having their ends turned inwardly beneath the bottom of said central electrode, and a second 60 pair of electrodes projecting from said face and having their ends turned inwardly beneath the ends of the first mentioned pair, the ends of each pair being in alignment 65 with each other.

5. In a spark plug having a threaded end within which is disposed a central electrode, a pair of complementary electrodes projecting from the face of said threaded end upon opposite sides thereof, said electrodes having their ends turned inwardly beneath the bottom of said central electrode, and a second 70 pair of electrodes projecting from said face and having their ends turned inwardly beneath the ends of the first mentioned pair, the ends of the first mentioned pair being at substantially right angles to the ends of the second mentioned pair. 75

In testimony whereof I have signed my name to this specification.

FRIEDERICH W. SCHMIDT.
